L. P. DITTEMORE

CIGAR LIGHTER

Filed July 14, 1926

INVENTOR.

BY LESTER P. DITTEMORE

H. G. Charles
ATTORNEY.

UNITED STATES PATENT OFFICE.

LESTER P. DITTEMORE, OF TOPEKA, KANSAS.

CIGAR LIGHTER.

Application filed July 14, 1926. Serial No. 122,421.

My invention relates to a cigar lighter, and has for its chief object, means to conceal the flames of burning embers as a safety device around escaping gases.

5 A further object of my invention is to provide an efficient means eliminating the use of batteries and fluid fuel.

A still further object of my invention is to provide a cigar lighting means having a 10 removable member to apply the flame of the ember for other lighting purposes.

A still further object of my invention is to provide a cigar lighter that is convenient to carry in the pocket and one that will contain a quantity of ignitable members.

A still further object of my invention is to provide a cigar lighter that will produce a flame by causing the ignition element to contact with a friction structure.

20 A still further object of my invention is to provide a cigar lighter having a visible means to ascertain the quantity of the ignition elements in storage.

These and other objects will hereinafter 25 be more fully explained.

Referring to the drawings:

Fig. 1 is a side view of the mechanism, parts broken away for convenience of illustration.

30 Fig. 2 is a transverse view, partly in section taken along line II-II in Fig. 1, looking in the direction of the arrows.

Fig. 3 is the opposite side view from that shown in Fig. 1.

35 Fig. 4 is a top view parts broken away for convenience of illustration.

Fig. 5 is an enlarged detailed view of the ignition means.

The mechanism herein disclosed consists 40 of a case 1 being made in two parts and separable along the line A as shown in Figs. 2 and 4. The said case functioning as a container for pellet like particles 2, the composition of which is adapted to ignite by

45 friction as hereinafter described. Concentrically positioned within the case is a receptacle 3 functioning as an ignition chamber. The said receptacle is composed of an annular structure having an inner and an outer wall 4 and 4'. The space between the walls is filled with asbestos fiber 5 as insulating means to prevent heat from transmitting therethrough to the pellets within the container obviating premature ignition.

50 55 Positioned on one side of the receptacle

and securely attached thereto is a finely woven wire fabric 6 functioning as a guard preventing flames from the ignited pellet to pass therethrough. On the opposite side of said chamber is a lid 7 hingedly attached to the case as at B and having a catch attaching means on the opposite side as at C, by which means the lid is held to a closed position.

Rigidly attached and concentrically positioned on the inside of said lid is a flange 8 being annular and made of finely woven wire fabric to function for the same purpose as the fabric on the opposite side in view of the reason that the lid 7 is spaced from the side of the case by legs 9 allowing the air to circulate through the ignition chamber, the said lid being means to prevent the burning embers from contacting the hand during the time of ignition. The annular 70 fabric may also be positioned as shown in Fig. 4, that is to say, the edges of the fabric instead of entering the chamber as shown in Fig. 2 will bear snugly on the case functioning as a separating means simultaneous 75 with the said legs. The lid functions as accessible means for removing sediment from the ignition chamber and also as means for exteriorly applying the flames which can not be done through the fabric.

80 Positioned within the case is a spring barrel 10 having a spring 11 pivotally mounted therein as at 12. The opposite end of the spring is adapted to reciprocate across the bottom of the hopper 13 as shown in Fig. 2 85 and Fig. 5. The said hopper converging to approximately the size of one of the pellets, terminating at the gate 14. The said spring having a suitable bend on the free end thereof is adapted to support the pellets positioned in the hopper delivering one at a time beneath the plunger 15 which is radially positioned within a sleeve 16 slidably engaging therein and tensioned by a recoil spring 16', the tendency of which is to eject the 90 plunger to the normal position as shown in Figs. 1 and 2. The inner end of the plunger is frusto-conical as shown at D. The outwardly extending end of the plunger has a disc like head 17 as contact means when 95 pressing the plunger inward. The said head also functions as a locking means to prevent inward movement by striking on a ring 18. The said ring is pivotally connected to the 100 case as at E and having a semi-circular loop 105 110

as at F so that the ring will swing to its normal position as shown in Figs. 1 and 2 and engaging under the head as preventing means for an inward movement of the

5 plunger. The said ring also functions as a means by which a chain or guard may be attached, and carried in the pocket.

Pivottally connected to the plunger is a yoke like member 19 functioning as a thrust 10 for the spring 11, the said yoke engages through apertures in laterally extending members from spring 11 as shown at 20 in Fig. 4. Positioned on the legs of the yoke are stops 21 by which means the said spring 15 11 is actuated throwing the curved free end of the spring near the wall of the spring barrel as shown in Fig. 5; which position will allow one of the pellets to pass between the lower end of sleeve 16 and the end of 20 said spring. The rebound of the spring will support the pellets remaining in the hopper.

It is now readily seen how the plunger in its reciprocations will drive the pellet in axial alignment therewith as shown in Fig. 1 25 driving it inward through a friction ignition means as shown at 22; said means being attached or integral with the inner end of the sleeve 16. Said ignition means being semi-circular and having slots 23 cut therein as 30 yielding means for the resiliency of the structure. The inside walls of said ignition means may be toothed or have a rough surface otherwise as means for igniting the pellet as it is driven inward to the ignition 35 chamber as shown in Fig. 5.

The gate 14 having a curvature on the disc like end thereof as at C is means to compress the pellet to close engagement with the ignition means and also functions as closing 40 means for the opening through which the end of the plunger enters the ignition chamber. The said gate being pivoted within the walls of said chamber as at 24 is tensioned by a spring 25 as closing means therefor. 45 To allow for the reciprocations of yoke 19, I have provided a stop 26 in opposite sides of the sleeve as shown in Fig. 5 and note that the recoil spring 16' engages on the shoulder on the inner end of the sleeve and yoke at its 50 pivot connecting point with the plunger. The free end of the spring 11 is guided through a slot in the spring barrel as at H.

The case is provided with an annular glass 27 as visible means to ascertain the quantity 55 of pellets contained within the case. On the opposite side of the case is a filling aperture having a cap 28 threadedly engaging therein; the face of which has cross cuts as at J as clinging means to the finger or thumb 60 when replacing or removing the same.

It will be understood that the fabric is not heated sufficient for lighting purpose; therefore the flame is drawn through the fabric by the usual suction through the cigar which is 65 pressed tightly against the fabric. It is now

readily seen why the mechanism is useful to prevent ignition of fumes from gasoline or other gases as the ignition of such must occur from the exposed flame.

The composition of the pellets is such that 70 they will ignite freely and the duration of burning is prolonged. Therefore they are adaptable for the purpose herein set forth but the formula or component parts are not claimed in this application. 75

Such modifications may be employed as lie within the scope of the appended claims.

Having thus described my invention, what I claim as new and desire to secure by Letters Patent is:—

1. In a cigar lighter, a case functioning as a container for ignitable pellets, an ignition chamber concentrically positioned in said case, woven wire fabric covering one end of said chamber, a lid having an annular woven wire fabric concentrically positioned thereon and adapted to encompass the opposite side of said chamber, a plunger radially positioned in said case, means for feeding the pellets beneath the inner end of said plunger, ignition means for the pellet when driven within said ignition chamber. 85

2. In a cigar lighter, a case functioning as a container for friction ignition pellets, an ignition chamber for said case, woven wire fabric as inclosing means for the sides of the chamber, a hopper, a spring, a plunger and a yoke actuating the spring by the reciprocations of the plunger as means for feeding the pellets consecutively through a friction 90 ignition means into the ignition chamber. 95

3. In a cigar lighter, a case functioning as a container for ignition pellets, a barrel, a spring within the barrel, laterally extending arms on the free end of the spring, a perforation in the outer end of each of the arms,

a sleeve having a plunger and a recoil spring therein, a hopper between the sleeve and the barrel for snugly passing the pellets to and in axial alignment with the plunger, a yoke pivottally mounted on the plunger, the opposite ends of the yoke engaging through the apertures in the ends of the laterally extending arms of the spring, stops on the yoke to engage with said arms on the spring as receding means for the spring when the stop is pushed inward, a friction ignition means attached to the inner end of the sleeve, a pivottally mounted gate for the end of said sleeve co-acting with the ignition means when the pellet is driven into the ignition chamber by said plunger, for the purpose described. 105 110 115

4. In a cigar lighter, a case functioning as a container for ignitable pellets, an annular glass on one side of the case as visible means for the contents, a plunger radially extending into the case, a threaded aperture having a cap as filling means for the container, a ring having a curvature transversely posi- 120 125 130

tioned to engage under the head of the plunger as locking means to prevent premature movement of the plunger.

5. In a cigar lighter, a case to contain a plurality of friction ignitable elements, an insulated ignition chamber concentrically positioned in the said case and extending from one side to the other, woven wire fabric closing the chamber on one side of the 10 case, a lid having a flange of woven wire fabric to close the opposite side of the chamber, the lid being spaced from said case for circulation of air through said chamber, a hopper having a separating means for the 15 ignitable elements so that one element at a time may be delivered into the ignition chamber, a plunger radially positioned and slidably engaging in a sleeve, the sleeve communicating with the ignition chamber, a 20 spring tensioned gate on the end of the sleeve, said gate being opened by the plunger forcing one of the ignitable elements into the ignition chamber and simultaneously closing as the plunger recedes.
- 25 6. In a cigar lighter, a case to contain ignitable pellets, a spring barrel and an ignition chamber rigidly connected, a leaf spring having laterally extending members near the

free end thereof, perforations in the ends of the members to receive the ends of an actuating yoke in such a way that the ends of the yoke may withdraw should the free end of the spring be detained, a slotted sleeve rigidly connected to the ignition chamber and to a peripheral point on the case, a 30 35 plunger and a recoil spring engaging within said sleeve, a yoke pivotally connected to the plunger as a bearing for the outer end of the spring, said yoke engaging through the apertures in the laterally extending members 40 of the leaf spring, a stop on both legs of the yoke to contact the laterally extending members of the spring causing it to recede for one of the ignitable pellets to pass inward to the gate beneath the end of the plunger 45 when the plunger has reached its normal position, and simultaneously the free end of the leaf spring functions as a stop for the remaining ignitable pellets, a ring pivotally connected to the case on opposite sides of the 50 plunger, a curvature in the ring to engage around the plunger so that the head thereof will prevent inward movement when the said ring is rocked to alignment therewith, all as, and for the purpose described.

LESTER P. DITTEMORE.
